IRVING F. NILES, OF PLAINFIELD, NEW JERSEY, ASSIGNOR TO R. HOE AND CO., OF NEW YORK, N. Y., A CORPORATION OF NEW YORK.

SHEET-FEEDING MECHANISM.

1,312,865.

Specification of Letters Patent.

Patented Aug. 12, 1919.

Application filed May 2, 1912. Serial No. 694,685.

To all whom it may concern:

Be it known that I, IRVING F. NILES, a citizen of the United States, residing at Plainfield, county of Union, and State of New Jersey, have invented certain new and useful Improvements in Sheet-Feeding Mechanisms, fully described and represented in the following specification and the accompanying drawings, forming a part of the same.

This invention relates to sheet feeding and sheet registering devices for printing machines, with particular reference to the feeding and registering of rigid sheets, such as those made of tin, or other metal, which are commonly handled in offset printing presses.

One object of the invention is to produce a machine in which the labor involved in handling sheets such as those of tin is reduced to a minimum.

Another object is to produce a machine in which the feeding of such sheets may be accomplished automatically and with certainty.

Still another object is to produce a machine which will effect a perfect registration of such sheets, both front and side.

With these and other objects not specifically referred to in view, the invention consists in certain constructions, and in certain parts, improvements and combinations as will be hereinafter fully described and then specifically pointed out.

Referring to the accompanying drawings:

Figure 1 is a plan of the feeding device.

Fig. 2 is a side elevation of the mechanism showing the sheet carriers.

Fig. 3 is a front elevation of the registering devices.

Machines embodying the invention will include devices for registering the sheets and feeding devices by which the sheets are delivered to registration devices, and these latter will be referred to first. While various means may be employed for delivering the sheets to the registering devices, in the construction shown these means will include feeding rolls 57 and 58 to which the sheets are fed in any suitable or desired manner. In the best constructions, the sheet will be fed between the rolls under comparatively light pressure.

As soon as the rolls have seized the sheet, however, the pressure may be increased to

great advantage. At the same time the sheet should be relieved of the pressure of the feeder so that there will be no tendency for the next sheet to be moved out of place as the top sheet is drawn through the rolls.

Mechanism to secure these results may be constructed in many forms, only one of which, however, is here necessary in order to disclose fully the invention. As shown in Figs. 1 and 2, the upper rolls 57, 57 are carried at the ends of a shaft 59 mounted in an arm 60 swiveled to a shaft 61, the two rolls resting upon two of the carrier tape rolls 58, 58 immediately beneath them and by which they are frictionally driven. A feeder rod 36 operating a pile feeder (not shown) carries an adjustable sleeve 62, the under side of which is provided with a cam surface 63. The arm 60 is equipped with a small roller 64 adapted to contact with the cam surface 63.

At the point where the feeder is moving to the left and the sheet has just entered the bite of the rolls 57 and 58, the cam surface 63 strikes the roller 64 and the rod 36 is thereby cammed upward. This relieves the pile of sheets of the weight of the feeder and at the same time throws this weight upon the arm 60 and rolls 57, thereby increasing the pressure between the rolls so that the sheet is drawn forward with certainty to the series of carrier tapes 65, 65 belted about the rolls 58. A second set of carrier tapes 66, 66 coöperate with the tapes 65, 65 to carry the sheet upon a pair of chains 67, 67 which are provided with suitable stops 68 against which the front edges of the sheet may be brought in a preliminary front registration movement.

This is effected by giving the carrier tapes 65 and 66 a more rapid movement than the chains 67, 67; the arrangement crowding the sheet upon the chains until its forward edge is arrested by contact with the stops 68 upon the chains. The length of the chains is equal substantially to the circumference of a sheet cylinder 69 and the chains and cylinder move at the same peripheral rate of speed.

By the mechanism thus far described, the sheet is brought into position for final registration before it is seized by the grippers mounted in the sheet cylinder. Mechanism constructed in accordance with the invention should accordingly provide means to effect front and side registration of the sheet at

this time. In the present illustration of such means, the front registration is secured by a stop 70 located upon the grippers 72 of the sheet cylinder 69, as is well shown in Fig. 2, 5 the edge of the sheet being brought up against this stop by the frictional drive of two drums 77, 78. The frictional rollers 73 and 74 which bear upon the sheet and rest upon the drums, as shown in Fig. 3, are 10 loosely mounted upon shaft 75, so that should the sheet have any skew, as it comes into contact with the gripper stops, the rollers 73 and 74 will permit the frictional drive of the drums below them to force the 15 sheet under one roller faster than under the other so that front registration may be attained.

A typical means of securing side registration in the embodiment of the invention is 20 shown in Fig. 3. The rollers 73 and 74 are rubber covered and are pressed by springs 76, 76 upon the iron drums 77, 78 carried by a shaft 79, driven by a centrally located gear 80. The rollers are movable longitudinally over the drums by means of a follower arm 81 fulcrumed at 82 and equipped with a roller 83 bearing upon a cam 84 mounted upon a collar 85 and driven from shaft 55. The follower arm spring is shown at 86. 25 The connection between the shaft 75 and the follower arm 81 is loose so that the shaft and rubber covered rollers have a swiveled movement to compensate for inequalities in the sheets which pass between these rollers 30 and the iron drums. As the machine is operated, the cam 84 forces the lower part of the follower arm to the right, as viewed in Fig. 3, causing a right hand movement of the rollers 73 and 74 upon the drums, thereby 35 crowding the sheet to the right. Coöperating with this mechanism is a registering stop 88 comprising a flanged friction roller mounted upon a micrometer slide 89 which is clamped to a reciprocating rod 90 having bearings 40 in the frame. Fulcrumed upon the frame at 91 is a follower arm 92 having a roller 93 engaging a cam 94 mounted upon one of the main shafts of the machine. The fol- 45

lower arm spring is shown at 95. The upper end of the follower arm engages a slotted 50 yoke 96 in the rod 90 so that the rod is reciprocated by the cam 94.

In operation, as the rollers 73 and 74 tend to crowd the sheet to the right, the right hand edge of the sheet is met by the advancing 55 stop 88 which limits its motion in that direction, thereby determining the registration.

The operative parts of the mechanism may be driven from the impression cylinder 60 through the gearing shown.

It will be understood that changes and variations may be made in the construction by which the invention is carried into effect. The invention claimed, therefore, is not to 65 be confined to the particular construction herein described and illustrated in the accompanying drawings.

What is claimed is:—

1. In a sheet feeding mechanism, an abutment, carrying devices adapted to move the sheet forward for front registration against the abutment, rollers in continuous contact with the sheet but permitting its free forward movement, the said rollers being 75 adapted to move the sheet laterally in one direction to effect side registration, an actuator to cause the transverse movement of the rollers, a side stop adapted to coöperate with the rollers to effect side registration, and an actuator for the side stop to cause a movement of the same in a direction opposite to that of the rollers.

2. In combination, a pair of rotary iron drums and a pair of loose friction rolls 85 spring pressed against the drums and rotatable therewith, and an actuating device to impart a longitudinal movement to the friction rolls with respect to the drums.

In testimony whereof, I have hereunto set 90 my hand, in the presence of two subscribing witnesses.

IRVING F. NILES.
